UNITED STATES PATENT OFFICE.

GEORGE H. CHINNOCK, OF BROOKLYN, NEW YORK.

MUSIC-SHEET FOR MECHANICAL MUSICAL INSTRUMENTS.

SPECIFICATION forming part of Letters Patent No. 443,252, dated December 23, 1890.

Application filed September 22, 1888. Serial No. 286,088. (No model.)

To all whom it may concern:

Be it known that I, GEORGE H. CHINNOCK, of the city of Brooklyn, in the county of Kings and State of New York, have invented 5 a certain new and useful Improvement in Music-Sheets for Mechanical Musical Instruments, of which the following is a specification.

In mechanical musical instruments the sound-producing devices of which are controlled by a traveling music sheet, card, or tablet it has heretofore been necessary to re-roll or move the music sheet, card, or tablet backward after playing and before the tune can be repeated or the continuance or change 15 of tune made.

The object of my invention is to obviate the necessity of thus stopping the instrument and rerolling or moving backward the music sheet, card, or tablet in order to arrange the 20 same and at the same time increase the capacity of music sheets, cards, or tablets by providing a music sheet, card, or tablet which for a given length will have a greater number of tunes than those heretofore used have 25 had, and also enable a tune or tunes to be repeated or continued.

To this end my invention consists, first, in a music sheet, card, or tablet for a mechanical musical instrument, having two sets of perforations representing different tunes, the 30 notes of one tune located between those of the other in the direction of the width of the sheet; second, in a music sheet, card, or tablet for a mechanical instrument adapted to produce two or more tunes by means of the 35 notes of a tune or tunes arranged intermediately between the notes of another tune or tunes in the direction of the width of the sheet, card, or tablet, and so arranged that a 40 tune or tunes may be played by moving the sheet, card, or tablet in one direction and the intermediate tune or tunes played by moving the music sheet, card, or tablet in the direction opposite to that in which it is moved for 45 playing the other tune or tunes; third, in a music sheet, card, or tablet adapted to reproduce one or more tunes by means of the notes of a tune or part of a tune arranged longitudinally in one direction, and the notes of 50 the same tune or part of the same tune arranged intermediately in the direction of the width of the sheet, card, or tablet between

the notes of the same tune or part of the same tune running in the opposite direction, so that by simply changing the direction of 55 movement of the music sheet, card, or tablet the tune may be repeated or continued.

The accompanying drawing represents a top view of a music sheet, card, or tablet embodying my improvement. 60

In the drawing similar letters of reference designate corresponding parts.

A designates a music sheet, card, or tablet made of paper, card-board, or other suitable material, and having the ends B and B' constructed in such a manner that they can be attached to reels for rolling and unrolling the same, the holes C and C' serving for the purpose of so securing the sheet to the reels by means of projections or slits in said reels. 70

The music-sheet A, instead of having only one series of perforations in its width, has two series. Those of one series a, which are designed to produce a tune or part of a tune when the sheet is moved in the direction of 75 the arrow b, are arranged intermediately between those of the other series a', which are designed to produce the remainder of the same tune or another tune or tunes when the sheet is moved in the opposite direction, as 80 shown by the arrow b'.

It will be obvious that by simply shifting the reed-board or music-sheet the air-ducts of the instrument can be brought opposite to the perforations a or a', as may be desired, and 85 if the direction of the movement of the sheet be reversed the change from one tune to another or the continuance or repeating of the same may be made instantly and without delay. It will be seen that this music-sheet is 90 novel, in that it has one or more tunes with their notes arranged intermediately.

By my invention I enable tunes to be played while the music-sheet is moving in either direction, and thus obviate the long delay required to reroll the ordinary music-sheet. 95

By the use of my improvement a portion of a tune may be played by moving the music-sheet in one direction and the remainder of the tune by moving the music-sheet in the opposite direction, or the whole of one tune may be played while the music-sheet is moving in one direction and the tune repeated by moving the sheet backward in the opposite direc- 100

tion, or that instead of the repeat another tune may be played; also, that two or more tunes may be played by having the tunes arranged longitudinally with the notes of one tune arranged intermediately between those of another tune or tunes in the direction of the width of the sheet.

My improvement has especial virtue, in that when it is desired to play "waltz" or "song" 10 music the same tune may be repeated or changed, as desired, without stopping or losing time, a thing impossible with the ordinary sheet.

What I claim as new, and desire to secure 15 by Letters Patent, is—

1. A music sheet, card, or tablet for a mechanical musical instrument having two sets of perforations representing different tunes, the notes of one tune being located between 20 those of the other in the direction of the width of the sheet.

2. A music sheet, card, or tablet for a mechanical musical instrument, adapted to produce two or more tunes by having the notes

arranged, as described, so that the notes of a 25 tune or tunes are intermediate between the notes of another tune or tunes, whereby a tune or tunes may be played by moving the sheet in a direction opposite to that in which it is moved for playing the tune or 30 tunes arranged intermediately and running in the other direction.

3. A music sheet, card, or tablet for a mechanical musical instrument, adapted to continue or repeat a tune or tunes by having 35 the notes of a tune or part of a tune arranged intermediately between the notes of the same tune or part of a tune or other tunes in a direction of the width of the sheet, so that the same tune may be repeated or the balance of the same tune continued by moving the sheet in a direction opposite to that in which it is moved for playing the same tune or part of a tune in the other direction.

GEO. H. CHINNOCK.
